US0D1064255S

(12) **United States Design Patent** (10) Patent No.: **US D1,064,255 S**
(45) Date of Patent: ** Feb. 25, 2025

(54) **ATOMIZER FOR MEDICINE**

(71) Applicant: **Andon Health Co., Ltd.**, Tianjin (CN)

(72) Inventor: **Ming Cong**, Tianjin (CN)

(**) Term: **15 Years**

(21) Appl. No.: **35/518,867**

(22) Filed: **Sep. 25, 2023**

(80) **Hague Agreement Data**

Int. Filing Date: **Sep. 25, 2023**

Int. Reg. No.: **DM/232537**

Int. Reg. Date: **Sep. 25, 2023**

Int. Reg. Pub. Date: **Nov. 3, 2023**

(30) **Foreign Application Priority Data**

Aug. 21, 2023 (CN) 202330533940.7

Primary Examiner — Richard Kearney

Assistant Examiner — Michael Hoffman

(57) **CLAIM**

The ornamental design for an atomizer for medicine, as
shown and described.

DESCRIPTION

1. Atomizer for medicine

2. Atomizer for medicine

1.1 : Front

1.2 : Back

1.3 : Left

1.4 : Right

1.5 : Top

1.6 : Bottom

1.7 : Front perspective view

1.8 : Back perspective view

2.1 : Front

2.2 : Back

2.3 : Left

2.4 : Right

2.5 : Top

2.6 : Bottom

2.7 : Front perspective view

2.8 : Back perspective view

(Continued)

The broken lines illustrate portions of the atomizer for medicine which form no part of the claimed designs.

1 Claim, 16 Drawing Sheets
